(57) **CLAIM**

The ornamental design for a refill container, as shown and described.

DESCRIPTION

FIG. 1 is a perspective view of a refill container showing our design in a dosing apparatus for environment;

FIG. 2 is a perspective view of the refill container;

FIG. 3 front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The dot-dash broken lines depict an environmental dosing apparatus that forms no part of the claim. The dash-dash broken lines depict portions of the refill container that form no part of the claim.

1 Claim, 6 Drawing Sheets
